UNITED STATES PATENT OFFICE.

CHARLES H. SCHNITZLER, OF CAMDEN, NEW JERSEY.

PNEUMATIC CONVEYER.

SPECIFICATION forming part of Letters Patent No. 412,985, dated October 15, 1889.

Application filed May 1, 1889. Serial No. 309,189. (No model.)

To all whom it may concern:

Be it known that I, CHARLES H. SCHNITZLER, of Camden, in the county of Camden and State of New Jersey, have invented a certain 5 new and useful Improvement in Pneumatic Conveyers, of which the following is a full, clear, and exact description.

My invention relates to a system of pneumatic conveyers, including a fan-blower and 10 main and branch pipes adapted to carry cotton or woolen fibers or shavings or other good or waste light material to any desired place of discharge by the blower.

The invention consists in certain novel 15 features of construction and combinations of parts of the pneumatic conveyer, all as hereinafter described and claimed.

Reference is to be had to the accompanying 20 drawings, forming a part of this specification, in which similar letters of reference indicate corresponding parts in all the figures.

Figure 1 is a vertical sectional view of adjacent portions of a mill and picker-house with my improved pneumatic conduits applied thereto and partly broken away. Fig. 2 is a front view, partly broken away, of a vertically-ranging pipe-conduit with branch pipes leading from it to either side. Fig. 3 is an enlarged view of part of the main-line 25 pipe and the connection of a branch pipe therewith, and as seen in direction of the arrow 1 in Fig. 2 of the drawings; and Fig. 4 is a detail view illustrating a pawl-and-ratchet lock device for the conveyer-valve.

The main pipe A of the conveyer system is 30 connected to a fan-blower B. The pipe and blower may have any relative arrangement, as the nature of the material to be conveyed and the preferred points of feeding and discharge of the material may require.

As a fair illustration of the improvement 35 I show the main pipe A ranging vertically through a mill-building C and extending therefrom to and within an adjacent picker-house D, where the fan-blower B is placed. The blower takes its air supply through a 40 pipe b', and its casing is provided with a hopper or funnel b, into which the picked or prepared cotton or woolen fibers or other material may be fed directly from the lower floor

or room d of the house D, or from the upper floor d' thereof through a funneled feed-pipe E, preferably having a telescoping feed-pipe e, which may be let down directly into the hopper b of the blower-casing, as occasion 55 may require. With this arrangement of the pipes, fan-blower, and blower feed devices it is obvious that the same blower may be used to take prepared cotton, woolen, or other fibers from two or more separate rooms in 60 the picker-house occupied by different manufacturers or tenants, to two or more separate floors or rooms in the main mill-building occupied by the same parties, and without danger of mixing the stock owned by different 65 tenants. This same blower would operate in like manner were the pipes all in the same building with it and leading from different points of feed to various places of discharge. The cotton, wool, or other material fed into 70 the blower-casing will be thrown therefrom by the air-blast of the fan into and through the main delivery-pipe A, from which it will be discharged at any one of several branch pipes connected to it, as the adjustment of a 75 series of valves fitted at the points of junction of the main and branch pipes may determine.

It will be noticed that the main pipe A extends from the picker house and blower into 80 the second story or floor of the mill-building C, and thence upward to the third and fourth floors thereof. Receiving-boxes c and c' are arranged at or along the mill on the second and third floors, respectively, one or more 85 receiving-boxes c² are located at the fourth floor, and receiving-boxes c³ c⁴ are arranged at the first floor. At the second floor the main pipe or conduit A is provided with two branch pipes F F', which project from it, one to the 90 right hand and the other to the left hand, as shown in Fig. 2 of the drawings, and valves f f', fitted at their joints with the pipe A, control the delivery of the cotton, wool, or other material either along the main pipe or to 95 either of these branch pipes. At the third floor there is fitted to the main pipe A a branch pipe G, which extends to the left hand and is controlled by a valve g, and at the fourth floor a branch pipe H, connected to the main 100

pipe, is shown extending toward the right hand and is controlled by a valve *h*. A lower branch pipe *I* extends from the main pipe *A* downward to the first floor, and is controlled 5 by a valve *i* at the joint with the main pipe, and is also provided with another valve *i'* to cause discharge into either of the boxes *c*³ *c*⁴ at will. It is manifest that the arrangement 10 of pipes shown is but one example of many 15 ways in which pipes extending from a fan-blower may be carried to discharge any materials at any required place or places.

All the valves *f* *f'* *g* *h* *i* *i'* are made practically alike, each consisting of a rectangular 15 plate of metal hinged at the point of junction of the main and branch pipes, and provided with a stem which projects through the pipes and at its end carries a cross-bar or head-piece *J*, with opposite ends of which are connected the ends of two pull cords or chains *K* *K*, which will extend to any place where they may be most conveniently handled to operate the valves. Where the valves are located 20 the pipe *A* will have a rectangular or box-like form, as shown at *a*, to allow the sides of the valves to fit closely, however the valves 25 may be adjusted.

It is manifest that when all the valves *i*, *f*, *f'*, *g*, and *h* are closed to or over the openings 30 of the pipes *I*, *F*, *F'*, *G*, and *H*, as shown in the drawings, the fan-blower will discharge the cotton, wool, or other material directly through the main pipe *A*, and from its open upper end supposed to turn to the left hand 35 into any one of a series of boxes *c*² in the upper floor of the mill. By opening any one of the uppermost valves controlling the pipes *H* *G* *F'* *F*, as indicated in dotted lines in the drawings, the cotton, wool, or other material 40 will be switched off from the main pipe *A* into the branch pipe. When the valve *h* is open, the material will be blown through the branch pipe *H*, and would pass along it to the right hand to any desired place of discharge. When the valve *g* is open, the material would pass through the pipe *G* to the left hand and to any one of a series of boxes *c'* on the third floor. When the valve *f* is open, the material would pass through 45 pipe *F* to the right hand, and when the valve *f'* is open the material would pass through the pipe *F'* to the left hand and to any one of the series of boxes *c* on the second floor. When the valve *i* is opened, the material would be switched into the pipe *I*, and should the valve *i'* be open the material would 50 pass into the first box *c*³; but if the valve *i'* be closed the material will pass on into the farther box *c*⁴, as will readily be understood.

55 The valves are so hinged that when they are closed to shut the mouths or inlets of the branch pipes the air-blast from the fan through the main pipe *A* in direction of the arrows 2 in the drawings would drive directly toward the free ends of the valves, on which the stock would be liable to catch unless prevented by some means, which I pro-

vide by fixing bracket-plates *L* on the inner faces of the valve-boxes *a*. These plates overhang the ends of the closed valves sufficiently 70 to compel the air-blast to carry the cotton or wool fibers or other material clear over and past the free ends of the valves. It will also be noticed that the arrangement of the valves is such that when any one valve is open to 75 compel discharge through one of the branch pipes there are no pockets or shoulders formed in the main pipe, into which some of the material would lodge, as occurs when two valves— 80 slide-valves, for instance—are used, one in the main pipe and the other in the branch pipe; hence when one of the valves *f* *f'* *g* *h* *i* *i'* is open all the material forced along the main pipe *A* from or by the blower will pass clear into and through the branch pipe controlled 85 by the valve, and when the valve is closed none of the material will remain in the main pipe *A* to be carried along through it with the next lot of cotton or other material blown through the main pipe. This feature of construction—namely, hinging the valve so that its free end directly faces or first receives the air-blast—wholly prevents the mixing of any portion of one lot of material with another 90 lot next blown through the main pipe, and which may be of an entirely different color or 95 nature, or may be the same in kind and quality, but belonging to another person using the fan-blower and pipes for conveying his stock. It will also be seen that when any one of the 100 valves is closed none of the material passing through the main pipe *A* will be caught by it; hence when the valve is next opened no material which should not pass to the branch pipe will enter it, and in this way also a mixture 105 of the stock or material will be avoided.

Although the cords *K* may be tied to a hook or peg to hold the conveyer-valve either closed or open, I prefer a separate lock device for this purpose. This lock consists of a 110 ratchet-wheel or segment *L*, fixed to the valve-stem, and a pawl *M*, pivoted to the main or branch pipe and pressed by a spring *m* into the ratchet. (See Fig. 4 of the drawings.) To the pawl, at one side of its pivot, is connected 115 a pull-cord *N*, which may be guided over suitable anti-friction pulleys *n* to any place from which the pull-cords *K* are operated. Another pull-cord *O* is connected to the pawl *M* at the other side of its pivot and leads to another picker-room or place to which the cords *K* may be connected, thus allowing disengagement of the pawl from the ratchet from 120 different rooms or places to which the cords *K* may be conducted or connected to allow the valve to be unlocked and either opened or closed and again locked from different points from or to which the material is to be taken.

Fig. 4 of the drawings represents a short 130 length of pipe *A'*, from which a branch pipe *A*² extends at right angles to discharge material carried by an air-blast moving through the pipe *A'* in direction of the arrow 3 and

against the open valve a' , which deflects it into the pipe A^2 , which leads to a storage bin or tank. When the valve a' is closed to the mouth of the pipe A^2 , the material will be carried past this pipe and along the pipe A' to any other place of discharge.

By employing two systems of pipes valved substantially as herein described and connecting them to one air suction and forcing apparatus material may be taken from one or more places by the air-suction through one set of pipes and may be forced by the air-blast to one or more places of discharge from the other set of pipes, thus effecting economical conveyance of material for different parties to and from different places by the same system of pipes and blower, as will readily be understood.

Having thus described my invention, what I claim as new, and desire to secure by Letters Patent, is—

1. A pneumatic conveyer for carpet, yarn, and woolen mills, consisting of a blower B ,

located in the picker-room and having a funnel b for the staple, a tube A , leading from the blower to the several stories of the mill and provided with branches $F F'$, valves ff' , hinged at their upper ends and extending downwardly over the branch openings, cross-bars J , connected to said valves and provided with cords for operating them, and the receiving-boxes on the several floors into which the branch pipes discharge, substantially as set forth.

2. In pneumatic conveyers, the combination, with main-line and branch pipes and a flap-valve hinged at their junction and provided with a cross-bar J and pull-cords K , of a ratchet L on the valve-stem, a spring-pressed pawl M , adapted to the ratchet, and pull-cords $N O$, connected to the pawl, substantially as herein set forth.

CHARLES H. SCHNITZLER.
